UNITED STATES PATENT OFFICE

155,107

DESIGN FOR A COMBINED APPAREL BELT
AND WRITING IMPLEMENT

Aaron Rothchild, Flushing, N. Y.

Application April 11, 1949, Serial No. 1,912

Term of patent 7 years

(Cl. D3—10)

To all whom it may concern:

Be it known that I, Aaron Rothchild, a citizen of the United States, residing at Flushing, in the county of Queens and State of New York, have invented a new, original, and ornamental Design for a Combined Apparel Belt and Writing Implement, of which the following is a specification, reference being had to the accompanying drawing, forming part thereof.

Fig. 1 is a front elevational view of a combined apparel belt and writing implement, showing my new design.

Fig. 2 is a top plan view thereof.

Fig. 3 is a view of a detail of the belt, drawn to an enlarged scale.

Fig. 4 is a right-hand end view of Fig. 3.

I claim:

The ornamental design for a combined apparel belt and writing implement, substantially as shown.

AARON ROTHCHILD.
